(57) CLAIM

The ornamental design for a dining chair, as shown and described.

DESCRIPTION

FIG. 1 is a front view of a dining chair showing my new design;

FIG. 2 is a rear view thereof;

FIG. 3 is a left side view thereof;

FIG. 4 is a right side view thereof;

FIG. 5 is a top view thereof;

FIG. 6 is a bottom view; and,

FIG. 7 is a perspective view thereof.

The broken lines depict portions of the dining chair that form no part of the claimed design.

1 Claim, 7 Drawing Sheets
